PLAYING CARDS

Richard E. Adams, Moorestown, N. J.

Application June 12, 1934, Serial No. 730,317

2 Claims. (Cl. 273—152)

This invention relates to an improved pack of playing cards and it is the purpose to provide a card game which lends amusement as an evening's pastime, as well as being educational and instructive for children as well as grown persons.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawing and claimed.

In the drawing:—

Figure 1 is a view of a group of cards showing the five vowels a, e, i, o, and u.

Figure 2 is a view of a group of picture cards, ten in all, each having a different picture, with the name of the character in the picture spelled out.

Figure 3 is a view of a group of forty seven cards containing substantially all the consonants.

Referring to the drawing numeral 5 identifies the cards in the first group showing the vowels, while 6 identifies the second group of cards shown in Figure 2. The group of cards 5 comprises twenty two cards containing four of the letter a, five of the letter e, seven of the letter i, four of the letter o, and two of the letter u, which assist materially in spelling the various words or names of the pictures in the group of ten cards identified by the numeral 6. The group of cards 6a, in Figure 3 have most all the consonants; b 2, c 4, d 3, f 1, g 2, h 1, k 2, l 4, m 1, n 4, p 4, r 5, s 7, t 4, v 1, y 1.

The group of ten cards 6 have various pictures, such as a grandfather's clock 8, a rabbit 9, a violin 10, a soldier 11, a candle 12, a kitten 13, a pup 14, scissors 15, a mouse 16 and a pig 17, the name of each picture being spelled on the same cards as identified at 18.

Rules of play

While it is possible to provide any suitable name or title, "Halt" is selected, because should a player play the wrong card, the player who first sees the mistake may shout "halt", which adds five points to the player's score.

In playing the game six cards may be dealt to each player, after which the remaining cards of the pack are placed in the center of the table.

The dealer starts the game by playing a picture card, but should the dealer not have a picture card the next player having a picture card starts the game.

The object is to spell the word on each picture card continuing until a player is out of cards. The second player may play either another picture card or the first letter of the word spelling the picture already played. If the second player cannot play he plays from the pack until he can play. Continuing, each player plays either a picture or the next letter of any word already played on the table.

The one who plays the last letter of any word takes the pile of cards (pictures and letters) and places it in front on the table. Each card thus won scores one point for the player at the end of the game. The game is over when the player plays his last card. All other players then give him all the cards still held in their hands and he adds them to his score.

If a player plays the wrong card, the first player who may see the mistake and shouts "halt" has five points added to his score. The player must take back his card and also lose his turn.

Scoring

Each card won (by playing the last letter of a word) (or from other players' hands by going out) counts one point. The winning score for the game is 200.

The invention having been set forth, what is claimed is:

1. A deck of playing cards comprising a group of cards having indicia of different tangible elements and additionally a second group of cards each bearing a letter of the alphabet, the cards of the last named group being present in the group in frequency approximating the frequency in their appearance in aggregate letters necessary to formation of the words commonly employed in denomination of the aggregate of said tangible elements.

2. A deck of playing cards comprising a group of cards each having a physical representation of an object having a distinctive name and a second group of cards each having an alphabetical indicia, said second group being capable of subdivision to produce individually in such subdivision all of the names of the representations of the first group.
